UNITED STATES PATENT OFFICE

101,763

DESIGN FOR A GUMMED SEAL OR SIMILAR ARTICLE

Mable J. Breen, Denver, Colo.

Application July 14, 1936, Serial No. 63,832

Term of patent 3½ years

To all whom it may concern:

Be it known that I, Mable J. Breen, a citizen of the United States of America, residing at Denver, in the county of Denver and State of Colorado, have invented a new, original, and ornamental Design for a Gummed Seal or Similar Article, of which the following is a specification, reference being had to the accompanying drawing, forming part thereof.

In the drawing:

Fig. 1 illustrates a face view of a seal showing my new design.

Fig. 2 is a side view thereof.

I claim:

The ornamental design for a gummed seal or similar article, as shown.

MABLE J. BREEN.
